UNITED STATES PATENT OFFICE.

REYNOLD O. JACOBSON, OF BANGOR, MAINE.

DESIGN FOR A BOOT-CALK.

SPECIFICATION forming part of Design No. 29,040, dated July 12, 1898.

Application filed May 7, 1898. Serial No. 680,065. Term of patent 7 years.

To all whom it may concern:

Be it known that I, REYNOLD O. JACOBSON, a citizen of the United States of America, and a resident of Bangor, Penobscot county, and State of Maine, have invented and produced a new and original Design for a Boot-Calk, of which the following is a specification.

The drawing represents in perspective a boot-calk, showing my design.

A boot-calk of my design consists of two portions—a shank portion *a*, slightly cone-shaped or tapering, having several encircling rings *b*, disposed upon the surface thereof and projecting therefrom, and a pointed portion *c*, tapering oppositely from said shank portion *a*, having disposed upon its surface a projecting ring *e*, to be referred to. At a point somewhat nearer one end of said boot-calk than the other end thereof and at the

point where said shank portion *a* joins with *c* said tapering pointed portion *c* a ring *d* appears, somewhat larger than said rings *b*, encircling said boot-calk and projecting beyond the surface thereof to form a shoulder, and a ring *e* appears upon said pointed portion *c* below said ring *d*, extending around the surface thereof and projecting therefrom, as shown in the drawing.

I claim—

The design for a boot-calk substantially as herein shown and described.

Signed by me, at Bangor, this 27th day of April, 1898.

REYNOLD O. JACOBSON.

Witnesses:

HENRY L. MITCHELL,
A. M. ROBINSON, Jr.
